UNITED STATES PATENT OFFICE.

EUGENE HAMEL, OF LYNN, MASSACHUSETTS, ASSIGNOR OF ONE-THIRD TO
BENJAMIN O. BELAND, OF MONTREAL, CANADA.

SHOE-PEGGING MACHINE.

SPECIFICATION forming part of Letters Patent No. 735,499, dated August 4, 1903.

Application filed December 13, 1902. Serial No. 135,046. (No model.)

To all whom it may concern:

Be it known that I, EUGENE HAMEL, a citizen of the United States, residing at Lynn, county of Essex, State of Massachusetts, have 5 invented certain new and useful Improvements in Shoe-Pegging Machines; and I do hereby declare that the following is a full, clear, and exact description of the invention, such as will enable others skilled in the art to 10 which it appertains to make and use the same.

This invention relates to machines for pegging boots and shoes or other materials to secure the soles to the uppers thereof, and it is of that class of pegging-machines which automatically severs the pegs from a strip or ribbon of peg-wood the width of which is equal 15 to the length of the pegs.

The main object of my present machine is to so simplify the construction of the machine as to enable it to perform all the work 20 performed by former machines of this class with greatly-simplified construction and a fewer number of parts, thus enabling the parts to be more strongly built and rendering 25 the machine less liable to repair as well as more accurate in its movements.

A special object that I have in view is to improve the peg-cutting mechanism in such manner that it will be no longer necessary to 30 set the machine by means of clamp-screws, dials, and other apparatus for each thickness of leather or other material and each individual shoe or set of shoes that are pegged in the machine; but, on the contrary, the machine 35 is always ready for use in any thickness of leather and will cut the pegs to the proper lengths at every point of the operation.

To these and other ends my invention consists, primarily, in reversing the process here- 40 tofore in use of cutting pegs of the proper length from the peg strip or ribbon, which former process consisted in first cutting the ribbon lengthwise to form a peg of the proper length, and, second, in splitting or slicing off 45 a peg from the ribbon thus cut, which peg was pushed by proper mechanism into the plunger-throat and thence driven by the driving-plunger or driver into the hole punched for it by the awl. In my machine, and 50 on the contrary, the peg is first sliced or split from the ribbon by the transverse knife, and

thereafter such peg is cut to the proper length, and to this end it is caused to be pushed down in a guideway a certain distance, determined automatically by the thickness of the stock 55 being operated upon, and then cut across by a V-shaped trimming-knife operated at the proper time, so that the end of the peg cut off falls away and the peg now trimmed to the proper length is pushed into the plunger-throat, as before. It will be observed in the sequel that this mode of operation has great 60 advantages over the other, primarily in enabling any width of ribbon to be used and in enabling the peg to be pointed at the same 65 time that it is cut by the V-shaped form of the knife.

My invention further consists in replacing the complicated mechanism which was heretofore employed to regulate and set the trimming-knife automatically by the vertical movements of the horn or other work-support caused by varying thicknesses of stock by a simplified mechanism consisting of a horizontal reciprocating cam which limits the downward movement of the reciprocating bar, to which is attached the pusher which pushes down the cut pegs successively to the proper distance to be acted on by the trimming-knife. 70 75 80

My invention further consists in the peculiar constructions and combinations which will be hereinafter more fully described and claimed.

I have illustrated my improvements in the 85 accompanying drawings, wherein—

Figure 1 is a side elevation of a complete machine embodying my improvements. Fig. 2 is a front elevation, on an enlarged scale, of the 90 head of the machine, including the awl and driving and cutting mechanism, the same being shown in their raised position. Fig. 4 is a similar view to Fig. 3, showing the same parts in their lowered position in the act of 95 driving the peg into the stock and punching the hole therein for the next peg. Fig. 5 is a left side elevation of the same parts as shown in Fig. 4. Fig. 6 is a right side view of the same parts, the front portions being shown 100 in central section on the line 66 of Fig. 4 and the remaining parts in elevation. Fig. 7 is a

horizontal section on the line 7 7 of Fig. 4. Fig. 8 is a reverse plan view of the lower end of the cutting and driving head, showing the positioning of the trimming-knife and its abutment-block. Fig. 9 is a side elevation of the trimming-knife and the parts coöperating therewith and showing also the lower end of the pusher and a peg in the act of being depressed in position to be cut by the trimming-knife. Fig. 10 is a side elevation of the member carrying the peg-strip guide and the plunger-throat of the peg-driver. Fig. 11 is a transverse section of the same on the line 11 11 of Fig. 10. Fig. 12 is a perspective view of the spring-finger employed to hold the pegs in place after being detached from the peg-strip or from a row of loose pegs and while being trimmed to the proper length. Fig. 13 is a vertical transverse sectional view of the detaching and trimming knives, showing their mounting in the knife-block; and Figs. 14 and 15 are perspective views of the trimming-knife and detaching-knife, respectively. Fig. 16 is a detail view of the parts carrying the peg-strip, showing the mode of trimming the pegs.

The same numerals of reference denote like parts in all the figures of the drawings.

As will be observed from the following specification and claims, the parts embodying my improvements lie exclusively in the upper part of the machine and relate to the work-head, which is designated by the numeral 16, the lower portions of the machine comprising a pedestal or standard 17 and a base-piece 18, to which it is secured and on which it rests and which are of the same form as in common use on this type of machine. At the upper end of the work-head 16 is journaled the usual horizontal front to rear main shaft 19 in journal-boxes 20 and having fast and loose pulleys 21 thereon, which operate the various working parts when the machine is in motion. About half-way down the standard 17 is journaled in a long bearing-box 22 the rock-shaft 23, carrying on its forward end a cylindrical vertical head 24, in which is reciprocably mounted the shank 25 of the horn 26, while the other end of the shaft 23 has fixed thereto by means of an adjustable segment 27 a rock-arm 28, which is caused to oscillate backward and forward at each complete rotation of the shaft 19 by means of the cam-roller 29, which is operated by a cam-wheel 30. The upper end of the horn 26 carries, as usual, an anvil 31, on which the shoe rests while being pegged and which supports the latter against the blows of the awl and peg-driver, while the lower end of the shank 25 of the horn is connected by a ball-joint 32 with a link 33, pivoted by a double or universal joint piece 34 to the treadle-lever 35, which is pivoted at 36 to the frame at the lower end of the standard 17. The treadle-lever 35 has at its front end a foot-plate 37 and at its rear end is overbalanced by a counterweight 38, being partially supported, as

usual, by the resilient spring 39, hung from the end of a bracket 40. The shank 25 has a shoulder at 41, so that when left to itself the counterweight 38 causes said shoulder 41 to rest against the lower end of the head 24, which limits the upward movement of the horn; but the latter may be readily depressed by the treadle-lever 35 without interfering with its oscillating movement, this latter being, of course, very small and merely sufficient to give the anvil 31 an intermittent movement of an amplitude equal to the distance between the successive pegs of the shoe. 80

On the front of the work-head 16 is mounted, as heretofore, a rocking head or block 42, which is mounted to oscillate on a pin 43, secured in the head 16 by means of a nut 44. This rocking head is given a very slight oscillatory movement, such that its lower end has an amplitude of movement equal to that of the anvil 31, so as to coact with it in feeding forward the shoe during the pegging-operation, and this motion is given to the rocking head 42 by means of a small eccentric cam-block 43^a, operating between the two rollers 44^a, on opposite sides thereof, carried by the two upstanding limbs 45, formed on the upper end of the rocking head 42, which is thus bifurcated, so as to receive the cam-block 43^a between the two limbs. 85

The rocking head 42 carries a vertically-reciprocating plunger-bar 46, which slides upward down in a suitable recess formed for it in the rocking head and whose front side is covered by a plate 47. The upper end of the plunger-bar 46 has an enlarged head 48, which carries a trundle-roll 49, mounted thereon and operating in a groove 50, formed in the face of the cylindrical cam-block 51, secured on the shaft 19, as shown, so that at the same time that the head 42 is being oscillated or otherwise moved from side to side the plunger-bar 46 is raised and lowered. At its lower end the plunger-bar 46 has formed therein a semicylindrical groove 52 for the awl 53, which is secured on the plunger-bar by a grooved clamping-block 54 and a screw 55. Side by side with the awl is mounted also the peg-driver 56, which is likewise secured to the plunger-bar 46 by a clamping-block 57 and screw 58, the driver 56 being held in parallel relation to the awl and its lower end being arranged to reciprocate in the tubular throat or guide 59, which is formed as a lug on the side of the guide-plate 60. (Shown in Figs. 10 and 11.) The guide-plate 60 is secured to the lower end of the rocking head 42 and oscillates with it and has, as shown, a turned-up flange 61 on its lower side, in which the peg-strip 62 runs. Any suitable mechanism may be employed for feeding forward the peg-strip, such as the usual pawl-and-ratchet-operated pair of gripping-wheels 62^a; but this forms no essential part of my present invention, and any of the well-known forms of feeding mechanism may be used therein. The flange 61 on the guide-plate 60 terminates ab- 125 130

ruptly short of the plunger-throat 59, leaving an open space between them, as shown at 63. The throat 59 has an overhanging laminar extension 64, which completely incloses the 5 end of the peg-strip; but the left-hand side of this extension, as shown in Fig. 10, also terminates short of the right-hand end of the flange 61, so as to leave room for the passage of the detaching-knife 65 between them.

10 When, therefore, the detaching-knife is operated to sever a peg 66 from the strip of material being fed along the guide-plate 60, it passes between the flange 61 and the extension 64, and the end of the strip is carried 15 under the latter, so that the detached peg is retained thereby. As, however, the lower end of this extension is open, it is necessary to provide means for supporting the detached pegs, which are normally two or three in number, (indicated at 66, 67, and 68,) and to this 20 end I provide a spring-plate 69, having a hole 70 at its upper end through which passes a screw 71, securing it to the upper end of the extension 64, and the lower end of the spring-plate 69 carries a small friction-block 72, which extends within a recess 73, formed in the lower end of the extension 64, and presses upon the several detached pegs 66, 67, and 68, thus preventing them from falling, while at 25 30 the same time permitting them to be readily pushed either sidewise or in a vertical direction. The feeding mechanism will cause the strip 62 to be pushed along step by step and at each motion will push the foremost peg 68 into the throat 59 and directly under the driving-plunger 56, by which it is immediately driven down and set in the stock; but before this takes place the peg is trimmed, if required, to the proper length in the following manner: The extension 64 has a longitudinal slot 74 therein, in which reciprocates the bent finger 75, formed on the lower 40 end of a pusher 76, which is clamped to a vertically-reciprocating pusher-bar 77, the 45 mounting and operation of which will be described hereinafter. The vertical reciprocation of the finger 75 is such as at each revolution of the shaft 19 to push down, if required, the detached peg 67 the requisite 50 amount, so that it will be cut off to the proper length by the trimming-knife 78, which is rigidly mounted, with the detaching-knife 65, in the manner which will be presently described. This trimming-knife has a channelled or V-shaped edge, as indicated in Figs. 13 and 14, so as to cut the peg crosswise to a sharp point, as indicated in Fig. 16, and the trimmed-off remnant 79 will drop on the floor or into any suitable waste-receptacle 55 60 65 70 75 80 85 90 95 100 105 110 115 120 125 130 135 140 145 150 155 160 165 170 175 180 185 190 195 200 205 210 215 220 225 230 235 240 tively detach the peg and trim it to the proper length, are both mounted rigidly on the lower end of a knife-holder 80, which is generally 70 of plate form and is pivotally connected at its upper end by means of a pin 81 to a lug 82, formed on the rocking head 42, while at an intermediate point of its length it is connected by a pin 83 with the lug 84, secured to the stationary head 16, this connection being such as to enable the free vertical movement of the knife-holder 80 relative thereto by means of a rectangular block 85, sliding in a guide-slot 86, formed in the knife-holder, 80 and the latter is further guided in its movement against wobbling by a projecting lug 87, which is recurved, so as to support both sides of the knife-holder. On its lower end the knife-holder has an aperture 88, through which passes the clamping-screw 89, which secures the two knives to the knife-holder; but any other means may be employed for this purpose. The trimming-knife 78 is formed as a projecting lug at the lower side 90 of a block 90, which has a horizontal fin 91 formed on its inner side and fitting into a corresponding groove 92 in the lower end of the knife-holder, and the block 90 is further provided with an elongated horizontal slot 93, through which the screw 89 passes. It will thus be seen that the two knives may each be adjusted laterally independently of each other and the knife-holder and clamped in the desired position, thus allowing for wear, while at the same time the fin 91 and the groove 94 prevent any possible twisting or displacement of the knives. The oscillating movement given to the rocking head 42 by the mechanism hereinbefore described is such as to cause the knife-holder 80 to have likewise a slight horizontal oscillating movement, so that when the lower end of the rocking head moves to the right as seen from the front, Fig. 3, the knives will be withdrawn from the peg-strip and the latter may be fed forward ready for driving another peg, and when the lower end of the head 42 is moved 120 toward the left the knife-holder 80 will be caused to oscillate about the pin 83 as an axis and both knives will be caused to cut the peg-strip, as before related, the detaching-knife 65 cutting off a peg and the trimming-knife 78 trimming a preceding peg to the proper length, and at the same operation the plunger 56 is thrust downwardly to drive the peg directly beneath it into the work.

I will now describe the operation of the 130 pusher 76, which is automatically operated to cause the peg to be cut to its proper length and which forms one of the most important and valuable features of my present invention.

tion. This pusher, as before described, is secured to the lower end of the pusher-bar 77 by means of a clamping-block 96 and a screw 97, and the pusher-bar is secured by guide-
 5 straps 98 and 99 to reciprocate vertically on the cover-plate 47 of the rocking head. Near its upper end is attached, by means of a pin 100, one end of a coiled spring 101, whose other end is secured to a pin 102 on the lower 10 guide-strip 99, the action of the spring 101 thus being to draw the pusher-bar downwardly to the lower limit of its movement. On the right-hand side of the pusher-bar is formed a projecting trip-lug 103, which projects over a vertical slot 104, formed in the plate 47 and through which projects a pin 105, secured to the driving-bar 46 and reciprocating therewith. The action of the pin 105 striking on the lug 103 is therefore 15 such as to raise the pusher-bar and pusher 76 at each rising movement of the plunger-bar 46. The lower limit of movement of the pusher-bar 77 is formed by a projecting lug 106 on the opposite side of the pusher-
 20 bar from the lug 103, on the end of which lug 106 is mounted a small roller 107, which rolls along the cam edge 108, formed on the horizontally-reciprocating cam-bar 109, whose forward end is guided by a strap 110, 25 secured to the rocking head 42, and whose other end is formed cylindrical and passes through a guide-lug 111 at the rear side of the stationary head 16. Between these two points of support the cam-bar 109 has formed 30 on its lower edge a series of rack-teeth 112, which gear with a toothed segment 113, formed on the upper end of a bell-crank lever 114, pivoted on a pin 115, projecting from the side of the work-head. The other end of the bell-
 35 crank lever 114 extends rearwardly and is connected by a long connecting-rod 116 with the forward end of the treadle-lever 35, and at an intermediate point the rod 116 may be 40 divided and have a turnbuckle 117 inserted therein for the purpose of adjusting its length and to properly regulate the position of the pusher with relation to the thickness of the stock, as will presently be described.
 It will be observed that the cam edge 108 is 45 formed of two horizontal portions 118 and 119, joined by an upwardly-sloping oblique portion 120, the purpose of this edge being to form, as above indicated, an adjustable lower limit for the movement of the pusher 76. It
 50 will be seen that in the reciprocation of the pusher by the means hereinbefore described, consisting of the reciprocating pin 105 acting on the lug 103, the pusher will be caused to rise above the top of the series of pegs and
 55 peg-strip, at which position the peg-strip will be automatically fed forward and will feed one peg 67 directly under the pusher-finger 75. Thereupon the pusher descends, depressing the cut peg 67, and the farther down it depresses it the shorter will the peg be cut by the operation of the trimming-knife 78, and therefore to cut the shortest possible pegs the
 60

finger 75 must be depressed to the greatest extent, and the roller 107 must therefore rest on the lower horizontal portion 118 of the cam edge 108, so that in this case the cam-bar 109 must be in the position shown in Fig. 6. On the other hand, to cut the longest possible pegs the cam-bar must be drawn back until the lower limit of the pusher-bar will be in 70 that position wherein the roller 107 rests on the upper horizontal portion 119 of the cam edge and the pusher-finger 75 will be depressed but very little and sometimes not at all. For intermediate lengths of peg the cam-bar must therefore be in intermediate positions, in which the lower limit of motion of the pusher will be regulated by the striking of the roller 107 on the oblique portion 120 of the cam edge 108. Now it will be observed 80 that the connection between the anvil of the horn 26 or other work-support and the cam-bar 109 is such as to regulate the length of the peg cut according to the thickness of the stock which is resting on the work-support or anvil 90 31 and held between it and the presser-foot 121, as shown at 122 in Fig. 4, for when the stock increases in thickness the horn 26 will necessarily be depressed, thus depressing the treadle-lever 35, causing the weight 38 to be 95 raised and drawing down the connecting-rod 116, which latter through its connection with the lever 114 will cause the cam-bar 109 to be retracted, thus raising the lower limit of motion of the pusher-bar in the manner before 100 described, and thus cutting off longer pegs. On the other hand, in case the thickness of the stock should decrease the weight 38 will cause the horn 26, which presses on the lower side of the stock, to rise, and thus will push 105 forward the cam-bar 109, permitting the spring 101 to draw the pusher-bar farther down, and thus shortening the length of the pegs cut off by the trimming-knife 78. If the turnbuckle 117 is properly set and the 110 pusher 75 properly clamped to the pusher-bar, so as to extend downwardly to the proper distance, the length of peg may be exactly regulated to the thickness of the stock, and this will be true for any stock whatever and 115 at every point of the operation, and thus no preliminary setting of the machine for different thicknesses of leather is required after it has once been properly adjusted. The work is set in the machine in the usual manner by depressing the foot-plate 37.
 The V-shaped trimming-knife 78 is arranged to cut against a triangular steel cutting-block 123, which is shown in reversed plan view in Fig. 8, and secured in position 120 by the chamfered edge of a clamping-block 124, secured to the under side of the head 42 by a screw 125.

It will be seen that this improvement gives very much greater simplicity of construction, 130 as well as efficiency in action over the old form, in that it avoids preliminary setting and substitutes simple and direct action with a minimum of operating parts. The pegs are

not only enabled to be pointed instead of merely edged, as heretofore, by a four-sided V-point, but, further, the width of ribbon or pegs used is immaterial and the operation of the machine independent of the character of the material pegged thereon.

While I have shown in the accompanying drawings the preferred form of my invention, it will be understood that I do not limit myself to the precise form shown, for many of the details may be changed in form or position without affecting the operativeness or utility of my invention, and I therefore reserve the right to make all such modifications as are included within the scope of the following claims or of mechanical equivalents to the structures set forth. It will also be obvious that my improvement is not restricted to the use of wooden pegs, as I also contemplate the use of pegs of leather and any other material which may be found suitable. I, however, wish to have it understood that although I have above described my machine as employed for pegging boots, shoes, and leather generally the machine may be employed for any use whatever, and I do not wish to restrict myself by the following claims to any particular use.

Having thus described my invention, what I claim as new, and desire to secure by Letters Patent, is--

1. In a machine for pegging, &c., the combination of means for feeding a peg-strip, means for detaching successive pegs, means for trimming each peg to the proper length and providing it with a V-shaped point at right angles to the edge of the strip, means for feeding forward the successive pegs after being trimmed, and means for successively driving the trimmed pegs.

2. In a machine for pegging, &c., the combination of a horn adapted to support the stock to be pegged, mechanism for feeding a peg-strip, a detaching-knife operated to detach successive pegs from said strip, a driver adapted to drive the detached peg into the stock, a trimming-knife between the detaching-knife and the driver adapted to cut off the peg, and a pusher operated to push the detached peg in the direction of its length a distance depending on the thickness of the stock for the operation of the trimming-knife.

3. In a machine for pegging, &c., the combination of a horn adapted to support the stock to be pegged, mechanism for feeding a peg-strip, a detaching-knife operated to detach successive pegs from said strip, a driver adapted to drive the detached peg into the stock, a trimming-knife between the detaching-knife and the driver adapted to cut off the peg, a pusher operated to push the detached peg in the direction of its length a distance depending on the thickness of the stock for the operation of the trimming-knife, and means connecting said horn with said pusher,

whereby the length of the trimmed peg is automatically adjusted to the thickness of the stock.

4. In a machine for pegging, &c., the combination of a support 26 on which the work rests, said support being reciprocable toward and from the stock, a driving-plunger, guides adapted to support a peg-strip, mechanism for feeding forward said peg-strip to feed the pegs under said plunger, a detaching-knife intermittently operated to detach successive pegs from the peg-strip, a trimming-knife between the detaching-knife and the plunger, a pusher adapted to push the detached peg into position to be cut off by said trimming-knife, and means connected with said work-support for regulating the distance through which the detached peg is pushed, substantially as described. 85

5. In a machine for pegging, &c., the combination of a support 26 on which the work rests, said support being reciprocable toward and from the stock, a driving-plunger, guides adapted to support a peg-strip, mechanism 90 for feeding forward said peg-strip to feed the pegs under said plunger, a detaching-knife intermittently operated to detach successive pegs from the peg-strip, a trimming-knife between the detaching-knife and the plunger, 95 a pusher adapted to push the detached peg into position to be cut off by said trimming-knife, means for resiliently drawing the pusher into its position nearest said trimming-knife, a stop adapted to limit the motion of said pusher toward the trimming-knife, and means connected with said work-support for adjusting the position of the stop according to the position of the support. 100

6. In a machine for pegging, &c., the combination of a V-shaped trimming-knife adapted to cut off and point each peg, means for pushing the successive pegs into position to be cut off by said trimming-knife, and means for regulating the movements of said pushing means depending on the thickness of the stock, whereby the appropriate length of peg is cut off. 105

7. In a machine for pegging, the combination of peg-driving means, a work-support co-acting therewith to support the work against the driving operation, said work-support being vertically movable toward and from said driving means, a presser-foot co-operating with said work-support to hold the upper surface of the stock in a fixed plane, means for yieldingly pressing said work-support toward the driving means to hold it against the opposite surface of the stock, means for feeding a peg-strip, means for successively detaching 115 pegs from said strip, means between said detaching means and driving means for trimming the length of the peg, a reciprocating pusher arranged to push the peg in the direction of its length a certain distance, whereby 120 to regulate the length to which it is trimmed, and a connection between said movable work- 125

130

support and said pusher, whereby the distance through which it pushes the peg is caused to vary with the thickness of the stock.

8. In a machine for pegging, &c., the combination of reciprocating peg-driving means, a work-support coacting therewith to support the work against the driving operation, said work-support being reciprocable toward and from said driving means, a presser-foot coöperating with said work-support to hold the surface of the stock adjacent to the said driving means in a fixed plane, means for yieldingly pressing said work-support toward the driving means to hold it against the opposite surface of the stock, means for feeding a peg-strip, means for successively detaching pegs from said strip, means between said detaching means and driving means for trimming the length of the peg, a reciprocating pusher arranged to push the peg in the direction of its length a certain distance, whereby to regulate the length to which it is trimmed, a reciprocating pusher-bar to which said pusher is attached, trip means operated by the reciprocating driving means for retracting said pusher at each backward stroke thereof, a variable stop limiting the movement of the pusher in the opposite direction, and a connection between said reciprocating work-support and said stop for varying the position of the latter.

9. In a machine for pegging, &c., the combination of reciprocating peg-driving means, a work-support coacting therewith to support the work against the driving operation, said work-support being vertically movable toward and from said driving means, a presser-foot coöperating with said work-support to hold the upper surface of the stock in a fixed plane, means for yieldingly pressing said work-support toward the driving means to hold it against the opposite surface of the stock, means for feeding a peg-strip, means for successively detaching pegs from said strip, means between said detaching means and driving means for trimming the length of the peg, a reciprocating pusher arranged to push the peg in the direction of its length a certain distance, whereby to regulate the length to which it is trimmed, a reciprocating pusher-bar to which said pusher is attached, trip means operated by the reciprocating driving means for raising said pusher at each backward stroke thereof, a cam movable to variable positions to vary the lower limit of said pusher-bar, and a mechanical connection between said cam and the lower end of said work-support, whereby the movement of said work-support away from said driving means caused by increased thickness of stock, causes said cam to be moved to retract the forward limit of movement of the pusher-bar, substantially as described.

10. In a pegging-machine, the combination of a driver, a work-support mounted to reciprocate vertically, means for longitudinally pressing said work-support upwardly against

the lower surface of the stock, a presser-foot coöperating with said work-support to hold the surface of the stock in a fixed plane, means for feeding a peg-strip sidewise toward said driver, means for successively detaching pegs from said strip as the latter approaches said driver, a reciprocating trimming-knife between said detaching means and said driver, and adapted to trim the pegs to a fixed length after being detached, and a vertically-reciprocating pusher adapted to push the detached pegs downwardly to be cut off by said trimming-knife, substantially as described.

11. In a pegging-machine, &c., the combination of a plunger-bar, a work-support mounted to reciprocate vertically, means for longitudinally pressing said work-support upwardly against the lower surface of the stock, a presser-foot coöperating with said work-support to hold the upper surface of the stock in a fixed plane, means for feeding a peg-strip sidewise toward said plunger-bar, means for successively detaching pegs from said strip as the latter approaches the plunger-bar, a reciprocating trimming-knife between said detaching means and said plunger-bar adapted to trim the pegs to a fixed length after being detached, a vertically-reciprocating pusher arranged to strike against the upper end of each peg as it is detached and push it downwardly to be cut off by said trimming-knife, and means connected with said reciprocating work-support for limiting the downward movement of said pusher to a variable extent, whereby an increased thickness of stock causes the diminished movement of said pusher.

12. In a pegging-machine, the combination of a vertically-reciprocating plunger-bar, a driver attached thereto and reciprocating therewith, a work-support mounted to reciprocate vertically, means for longitudinally pressing said work-support upwardly against the lower surface of the stock, a presser-foot coöperating with said work-support to hold the upper surface of the stock in a fixed plane, a guide-throat in which said driver reciprocates, means for feeding a peg-strip sidewise toward said guide-throat, means for successively detaching pegs from said strip as the latter approaches the guide-throat, a reciprocating trimming-knife between said detaching means and said guide-throat adapted to trim the pegs to a fixed length after being detached, a vertically-reciprocating pusher arranged to strike against the upper end of each peg as it is detached and push it downwardly to be cut off by said trimming-knife, means for resiliently drawing the pusher into its lowermost position, means for raising said pusher at each rising movement of the driver, a variably-positioned stop limiting the descending movement of said pusher, and means connecting the said work-support with said variable stop, whereby the distance through which said pusher moves is caused to vary with the thickness of the stock.

13. In a pegging-machine, the combination of a vertically-reciprocating plunger-bar, a driver secured to the lower end of said bar, a yieldably-mounted vertically-reciprocating work-support adapted to support the work against the action of said driver, means for yieldingly pressing said work-support against the lower surface of the stock, a presser-foot coöoperating with said work-support to hold the upper surface of the stock in a fixed plane, a guide-throat in which the lower end of said driver reciprocates, means for feeding a peg-strip sidewise toward said guide-throat, a reciprocating detaching-knife operated to detach a peg from said strip at each complete cycle of the machine, a trimming-knife operating to cut off the end of said detached peg to trim it to a proper length, a vertically-reciprocating pusher having a finger adapted to strike the head of the detached peg and push it downwardly a certain distance, a vertically-reciprocating pusher-bar to which said pusher is secured, means for resiliently holding said pusher-bar in its lowermost position, tripping means carried by said plunger-bar, a projection on said pusher-bar against which said tripping means strikes at each upward movement of said plunger-bar to raise said pusher-bar, a reciprocating cam having an inclined edge, said pusher-bar having a projection resting against said edge, whereby said edge forms the lower limit of movement of said pusher-bar, and a mechanical connection between said cam and said work-support, whereby said cam is moved laterally when said work-support is depressed by the thickness of the stock, so as to raise the lower limit of movement of said pusher-bar.
14. In a pegging-machine, the combination of a plunger-bar, a vertically-reciprocating work-support coacting to support the work against said plunger-bar, a treadle-lever to which the lower end of said work-support is connected, a counterweight carried by the rear end of said lever causing said work-support to be yieldingly pressed against the lower surface of the stock, means for feeding a peg-strip sidewise toward said plunger-bar, means for detaching successive pegs from said strip as it approaches said plunger-bar, a trimming-knife between said detaching means and plunger-bar, a vertically-reciprocating pusher acting to push each detached peg downwardly to be cut off by said knife, means for raising said pusher at each revolution of the driving-shaft, a variable stop against which said pusher normally rests in its lowermost position, and a connection between said treadle-lever and said stop for varying the position of the latter, whereby the length of peg is varied according to the thickness of the stock.
15. In a machine for pegging, &c., the combination of a work-head, a rocking head mounted thereon, means for giving said rocking head a slight oscillating movement from side to side, a plunger-bar mounted in said
- rocking head, a knife-block pivoted on said stationary work-head and pivotally connected with said rocking head and receiving a slight oscillating movement therefrom, a guideway for a peg-strip, and means for feeding said peg-strip therethrough toward said plunger-bar, a detaching and trimming knife both secured to the lower end of said knife-block and operating against said peg-strip as it approaches said plunger-bar, said trimming-knife being located between said detaching-knife and said plunger-bar, and a vertically-reciprocating pusher adapted to strike the head of each peg as it is detached, and push it within range of said trimming-knife.
16. In a machine for pegging, &c., the combination of a work-head, a rocking head mounted thereon, means for giving said rocking head a slight oscillating movement from side to side, a plunger-bar mounted in said rocking head, a knife-block pivoted on said stationary work-head and pivotally connected with said rocking head and receiving a slight oscillating movement therefrom, a guideway for a peg-strip, and means for feeding said peg-strip therethrough toward said plunger-bar, a detaching and trimming knife both secured to the lower end of said knife-block and operating against said peg-strip as it approaches said plunger-bar, said trimming-knife being located between said detaching-knife and said plunger-bar, a vertically-reciprocating pusher adapted to strike the head of each peg as it is detached, and push it within range of said trimming-knife, means for resiliently holding said pusher at the lower limit of its movement, means for raising said pusher at each revolution of the driving-shaft, and a variable stop against which said pusher rests in its lowermost position.
17. In a machine for pegging, &c., the combination of a work-head, a rocking head mounted thereon, means for giving said rocking head a slight oscillating movement from side to side, a plunger-bar mounted in said rocking head, a knife-block pivoted on said stationary work-head and pivotally connected with said rocking head and receiving a slight oscillating movement therefrom, a guideway for a peg-strip, and means for feeding said peg-strip therethrough toward said plunger-bar, a detaching and trimming knife both secured to the lower end of said knife-block and operating against said peg-strip as it approaches said plunger-bar, said trimming-knife being located between said detaching-knife and said plunger-bar, a vertically-reciprocating pusher adapted to strike the head of each peg as it is detached, and push it within range of said trimming-knife, means for resiliently holding said pusher at the lower limit of its movement, means for raising said pusher at each revolution of the driving-shaft, a variable stop against which said pusher rests in its lowermost position, a vertically-yieldable work-support beneath said rocking head, means for resiliently press-

ing said support against the lower side of the stop, and a connection between said work-support and said variable stop, whereby the depression of said support causes said stop to be raised, thus cutting off longer pegs.

18. In a pegging-machine, peg cutting and trimming mechanism comprising a guideway through which a peg-strip is adapted to be fed, a guide-throat at the end of said guideway which holds the pegs in position to be driven, a reciprocating detaching-knife operating across said guideway to detach successive pegs, a reciprocating trimming-knife between said detaching-knife and guide-throat acting on the lower ends of the pegs after they are cut off, a spring-pressure block adapted to hold said pegs lightly in the position in which they are placed, and a pusher adapted to depress successive pegs within range of action of the trimming-knife.

19. In a pegging-machine, detaching and trimming mechanism comprising a reciprocating knife-block having a horizontal groove and a hole near its lower end, an independent block 90 carrying a detaching-knife and having a horizontal fin adapted to fit in said groove, and a horizontal slot therein, a plate having a sharpened edge and forming a detaching-knife, said plate having a horizontal slot therein corresponding in position with the slot in said block, a horizontal seat in said block 90 against which the lower edge of said plate is adapted to rest, and a bolt adapted to pass through the hole in the knife-block and through the two slots to secure the parts adjustably in position.

20. In a pegging-machine, the combination of cutting and trimming mechanism adapted to cut a peg from a peg-strip and trim it to the proper length, comprising a plate-shaped member 60, a tubular lug formed thereon at one side thereof forming a guide-throat in which the driver is adapted to reciprocate, said lug having an overhanging flange extension 64, a flanged guide 61 adapted to guide the peg-strip laterally, a spring-pressure block 72 adapted to press frictionally against the sides of the detached pegs, means operating between the end of the guide-flange 61 and the adjacent side of the extension 64 for detaching the pegs from the strip, said flange extension having a vertical slot 74 therein, a vertically-reciprocating pusher-finger 75 operating in said slot and adapted to strike against the heads of the successive detached pegs, and a trimming-knife directly under said pusher-finger adapted to cut off the end of the peg to the proper length, substantially as described.

21. In a pegging-machine, peg detaching and trimming mechanism comprising a plate member 60, having a tubular lug 59 forming a guide-throat formed on one side thereof, a flange extension 64 formed on one side of said guide-throat through which the pegs pass to said throat, a guide-flange 61 adapted to guide the peg-strip, an oscillating knife-block piv-

oted to the frame of the machine, means for oscillating said block backward and forward at each revolution of the driving-shaft, a vertical plate-shaped detaching-knife secured to the lower end of said block and reciprocating across the path of the peg-strip between the end of said guide-flange and said flange extension, an independent block 90 carrying at its lower portion a V-shaped projecting trimming-knife adapted to reciprocate across the path of the detached pegs and likewise secured to the lower end of said knife-block, a plate-spring 69 secured to the upper end of said lug, a friction-block 72 carried by the lower end of said plate-spring and extending through a recess in said lug and pressing against the sides of the detached pegs to hold them frictionally in position, said flange extension having a vertical slot therein, a pusher 76 having a horizontally-bent finger extending through said slot and reciprocating therein, a vertically-reciprocating work-support, means for resiliently holding said support against the lower surface of the stock, feed mechanism adapted to feed forward the peg-strip at the proper intervals by one peg at a time, means for raising said pusher at each forward movement of the feed mechanism, means for subsequently lowering the same to push the detached peg immediately under it downwardly to be cut off by said trimming-knife, a variable stop having an inclined edge determining the lower limit of movement of said pusher, and a connection between said work-support and stop, whereby the downward movement of said pusher is adjusted to the thickness of the stock.

22. In a pegging-machine, peg detaching and trimming mechanism comprising a guideway through which a peg-strip is adapted to be fed, feed mechanism adapted to feed forward the peg-strip through said guideway, a guide-throat formed at the end of said guideway in which the peg-driver reciprocates, a knife-block pivotally mounted on the frame of the machine, means for oscillating said knife-block, an independent block 90, and a detaching-knife secured thereto, both being secured to the lower end of said knife-block, a V-shaped forwardly-projecting trimming-knife, both of said knives projecting forwardly across the path of said strip, and a V-shaped cutting-block coacting with the edge of said trimming-knife and against which the latter slides, said cutting-block being secured to the lower side of the parts carrying the guideway and at right angles to the latter, substantially as described.

23. A pegging-machine, comprising a vertical standard, a work-head mounted on the upper end thereof, a work-shaft rotatably mounted at the upper end of said work-head, a rocking head mounted to oscillate on the front side of said work-head, an eccentric cam-block operating in a slot at the upper end of said rocking head and giving the latter a slight oscillatory movement, a verti-

cally-reciprocating plunger-bar mounted in said rocking head, a cam-block mounted on said work-shaft and having a groove therein, a pin on the upper end of said plunger-bar 5 operating in said cam-groove, whereby the plunger-bar is reciprocated vertically, a peg-driver secured to the lower end of said plunger-bar, a guide-throat in which the lower end of said driver reciprocates, a guideway 10 through which a peg-strip is fed sidewise to said guide-throat, feed mechanism adapted to feed said peg-strip intermittently forward as the successive pegs are driven, a vertical knife-block pivoted on the frame of the machine and connected at its upper end with said rocking head, whereby to receive an oscillatory movement from the latter, a vertical detaching-knife secured to the lower end of said knife-block and reciprocating through 15 a slot in said guideway across the path of the peg-strip, a forwardly-projecting V-shaped trimming-knife also secured to the lower end of said knife-block on the side of the detaching-knife next to the driver, said trimming-knife being arranged to reciprocate across the path of the lower end of the detached pegs, a V-shaped cutting-block secured to the lower end of the rocking head and coacting 20 with the edge of said V-shaped trimming-knife, a vertically-reciprocating pusher having a bent finger operating in a vertical slot in the guideway immediately above said trimming-knife, whereby to strike against the upper end of the detached pegs and push them 25 downwardly into range of said trimming-knife, a spring-pressed block 72 pressing against the side of the detached pegs to hold them in position, a pin projecting from the side of said plunger-bar, a pusher-bar to the lower end of which said pusher is secured, said pusher-bar being arranged to reciprocate 30 vertically in guides, means for yieldingly holding said pusher-bar at the lower limit of its movement, a projection on said pusher-bar against which said pin on the plunger-bar is adapted to strike in its upward movement, whereby to raise said pusher just prior to the forward movement of the feed mechanism, a second sidewise projection on said 35 pusher-bar, and a variable stop having an inclined edge against which said projection is adapted to rest, whereby the lower limit of movement of the pusher may be varied.

24. A pegging-machine, comprising a vertical standard, a work-head mounted on the upper end thereof, a work-shaft rotatably mounted at the upper end of said work-head, a rocking head mounted to oscillate on the front side of said work-head, an eccentric cam-block operating in a slot at the upper end of said rocking head and giving the latter a slight oscillatory movement, a vertically-reciprocating plunger-bar mounted in said rocking head, a cam-block mounted on said 40 work-shaft and having a groove therein, a pin on the upper end of said plunger-bar 45 operating in said cam-groove, whereby the plunger-bar is reciprocated vertically, a peg-driver secured to the lower end of said plunger-bar, a guide-throat in which the lower end of said driver reciprocates, a guideway through which a peg-strip is fed sidewise to said guide-throat, feed mechanism adapted to feed said peg-strip intermittently forward as the successive pegs are driven, a vertical 50 knife-block pivoted on the frame of the machine and connected at its upper end with said rocking head, whereby to receive an oscillatory movement from the latter, a vertical detaching-knife secured to the lower end of said knife-block and reciprocating through a slot in said guideway across the path of the peg-strip, a forwardly-projecting V-shaped trimming-knife also secured to the lower end of said knife-block on the side of the detaching-knife next to the driver, said trimming-knife being arranged to reciprocate across the path of the lower end of the detached pegs, a V-shaped cutting-block secured to the lower end of the rocking head and coacting 55 with the edge of said V-shaped trimming-knife, a vertically-reciprocating pusher having a bent finger operating in a vertical slot in the guideway immediately above said trimming-knife, whereby to strike against the upper end of the detached pegs and push them downwardly into range of said trimming-knife, a spring-pressed block 72 pressing against the side of the detached pegs to hold them in position, a pin projecting from the side of said plunger-bar, a pusher-bar to the lower end of which said pusher is secured, said pusher-bar being arranged to reciprocate 60 vertically in guides, means for yieldingly holding said pusher-bar at the lower limit of its movement, a projection on said pusher-bar against which said pin on the plunger-bar is adapted to strike in its upward movement, whereby to raise said pusher just prior to the forward movement of the feed mechanism, a second sidewise projection on said pusher-bar, a horizontally-reciprocating cam-bar 109, having an inclined cam edge 108, against which said projection on the pusher-bar rests, a work-support mounted to reciprocate vertically, a presser-foot 121 adapted to hold the upper surface of the stock in a fixed plane, a treadle-lever to which the lower end of said work-support is connected, means for resiliently holding said treadle-lever in raised position, and a connection between said treadle-lever and said reciprocating cam-bar, whereby the depression of said treadle-lever causes the cam-bar to be moved in a direction to raise the lower limit of movement of the pusher-bar, 115 substantially as described.

In witness whereof I have hereunto set my hand in the presence of two witnesses.

EUGENE HAMEL.
